UNITED STATES PATENT OFFICE.

BERNARD LIBERMAN, OF PHILADELPHIA, PENNSYLVANIA.

METHOD AND MEANS FOR CIGAR BUNCHING.

Application filed December 6, 1920. Serial No. 428,547.

To all whom it may concern:

Be it known that I, BERNARD LIBERMAN, a citizen of the United States, residing at Philadelphia, in the county of Philadelphia, 5 State of Pennsylvania, have invented a new and useful Method and Means for Cigar Bunching, of which the following is a specification.

My invention relates to cigar bunching.

10 The object is to provide improved method and means for operating upon the binder so that the same shall be properly stretched and smoothed while being rolled about the filler, but in such manner that the binder 15 shall not be unduly stretched, torn or otherwise injured during said operation.

In order properly to understand and appreciate the invention, it should be borne in mind that the binder comprises a portion 20 of a slightly moistened or damp tobacco leaf. It may be of one or more ply. In texture this binder is to a certain extent porous and fragile. Undue strains or pressures will break or tear it. It is therefore 25 very important that, in rolling this binder, about the filler, it should have all wrinkles removed therefrom, without subjecting any part thereof to a greater tension than it will safely stand.

30 It is well known that even in drawing the binder gently between the fingers of the operator, in order to smooth out the wrinkles, it is not always possible to avoid tearing the same.

35 I have found that this difficulty can be almost entirely eliminated by drawing the binder between the roller, or to be exact, between the portion of the apron which surrounds the roller, and the ends of the bristles 40 or hairs of a comparatively soft brush, the engaging surface of which extends parallel with the roller. This is because the individual ends of the bristles, each exerts a yielding and independently movable pressure on that particular part of the leaf with

45 which it contacts. The result is, a progressive and gradual operation of successive bristles, where necessary, upon a wrinkle or unevenness in the binder; this eliminates undue stresses upon any part of the leaf, and at the same time secures a maximum of smoothness as the binder is rolled upon the filler.

In the use of the word bristle, I wish to 55 include any similar material such as hair or other substance comprising a number of

strands or filaments, the aggregate of which comprise the engaging surface.

This brush I term a smoothing element, and the invention comprises the application 60 of the same in combination of the other and usual elements of a cigar bunching machine, in the particular way herein specified, to the smoothing and tensioning of the binder as it is rolled about the filler. I refer especially to the manner in which the engaging point or end of each individual bristle has an independently movable yielding or 65 resilient action upon the texture of the leaf, while at the same time the several succeeding bristles have a gradual, progressive and cumulative action upon any particular point of difficulty on the leaf. It should also be noted that, in view of the extremely yielding and resilient action of the smoothing 70 element, a binder, either of single ply or of multiple ply may be used with satisfactory 75 results.

The invention also comprises the method and means whereby the brush is carried, 80 guided and positioned so that the individual bristles will be directed toward the binder at the required or most effective angle.

Referring to the drawings, which illustrate merely by way of example, suitable 85 means for effecting my invention, and also in a diagrammatic way the method of operation;

Fig. 1 is a side elevation partly in section of mechanism for effecting the invention. 90

Fig. 2 is a plan view of same.

Fig. 3 is a section on the line 3—3 of Fig. 2.

Fig. 4 is a fragmentary section on same line as Fig. 3, with parts in different position. 95

Fig. 5 is a cross-section on line 5—5 of Fig. 2.

Figs. 6 to 10 inclusive, are diagrammatic views showing the progressive steps in the 100 bunching operation.

Similar numerals refer to different parts throughout the several views.

The general construction and operation of the machine is similar to that shown in 105 my co-pending application Serial No. 315,000 filed Aug. 2nd, 1919, and no claim is made herein for such general construction and operation except that part which relates to the brush, its operation and functions. 110

The bunch rolling table 15 is supported on any suitable frame such as 16, and is pro-

vided with the slide rods 17 upon which is slidably mounted the carriage 18 carrying the arms 19 having the slots 20 in which are adjustably secured the ends of the roller 5 journal 21. This carriage 18 is connected with any suitable actuating means for causing its reciprocation upon the slide rods 17. The usual bunching apron 22 is connected or secured at each end to the table 15 by 10 any suitable means as indicated. The table 15 is also provided with a transversely arranged trough or pocket 23 for receiving the apron and filler in the manner well known in the art.

15 A long narrow brush 24 is provided having its engaging edge extending parallel with the roller 25, and approximately the same length as the roller. This brush 24 has a body portion 26 which is adjustably 20 connected to the frame 27 having side arms 28 provided at their lower extensions with pivots 29, extending into slots 30 provided in the ends of brackets 31 extending downwardly from the carriage 18. Springs 32 are connected at one end of each to an arm 28, at the other end to an arm 19 substantially as indicated. Stops 33 are threaded, or otherwise adjustably connected, with arms 19 for engaging the side-arms 28 or 30 projections such as 34 therefrom, and projections or pins 35 are provided on the carriage 18, for engaging said side arms 28.

35 The method, or operation of bunching according to the present invention is as follows:

In the initial position the brush 24 and roller 25 are brought into the relative positions shown in Figs. 3 and 6, with the front edge of the brush projecting close to the 40 margin of the pocket 23. In the present example where an automatic filler charging device is used, the binder 36 is laid across the brush 24, with its end extending onto the part of the apron 22 which lies over the pocket or trough 23. The charging funnel 37 is then depressed into the position shown in Fig. 7. This carries the apron 22 down to the bottom of the pocket and also carries the end of the binder 36 down into 45 one side of the pocket as shown. The plunger 38 then forces the filler 39 out of the charging funnel 37, as the funnel is elevated out of pocket 23 leaving the filler therein. By actuating the carriage 18 the 50 roller and brush then come into the positions shown in Fig. 8, that is, the position in which brush and roller meet over the middle of the trough or pocket; the brush carrying the binder with it and the roller carrying the apron, so that the binder and apron entirely enclose the filler within the 55 pocket.

60 It might be noted here that in the position shown in Fig. 3, the brush and roller are kept apart to permit the introduction

of the filler, between the two, into the pocket 23. This is accomplished by the construction shown in this figure. The arms 28 are rigid with the frame 27 carrying the brush body 26. The arms 28 are held in the position shown in this figure, against the tension of springs 32 by the engagement of the arms 28, against the pins 35 projecting from the table 15. When the arms 19 move toward the left, the pivot pins 29 move upwardly to the right hand end of slots 30, and then, as the carriage 18, moves further to the left, the arms 28, responding to the pull of springs 32, (the pins 35 being relatively withdrawn) move in the clockwise direction, causing an elevation and tilting of the brush into the position shown in Fig. 4, with the arms 28 or the projections 34 thereof resting against the stops 33 on arms 19. And this is the approximate 70 relative position maintained by the brush with respect to the roller throughout the balance of their reciprocating movements, except that the brush is tilted slightly more in the later positions, as in Figs. 9 and 10. 80 As the bunch moves to the opposite side of the roller from the brush, the brush assumes a more truly wiping position, which is the ideal position for best efficiency during the wrapping of the last part of the 85 binder on the bunch. This relative position, of course being adjusted at will, by adjusting the stops 33. By this adjustment, the pressure of the brush against the binder may be increased or diminished as required, depending upon the character of the binder used.

90 From the position shown in Fig. 8, the roller and brush travel to the left. In Fig. 9 the bunch is shown just leaving the pocket, with a substantial portion of the binder rolled about the filler, all of the binder so rolled about the filler, except the end shown projecting beyond the brush in Fig. 8, has 95 been drawn between the brush and roller as both are moving toward the left. Fig. 10 shows a still later stage, just as the last part of the binder is being drawn between the brush and roller, or more strictly between the brush and the part of the apron 100 which covers the roller adjacent to the brush.

110 As above indicated, since every part of the binder leaf is required to pass under the smoothing influence of a number of separate and individual bristle points in succession, the effect of the action of these several independently movable bristle points is progressive and cumulative, resulting in a 115 gradual but finally complete smoothing out of all creases and wrinkles in the binder and without the slightest danger of tearing or distorting the same. At the same time gentle but sufficient tension is exerted upon the binder at the points and to the ex- 120 125 130

tent required to secure an even rolling of the binder about the filler.

The smoothing out is accomplished principally in the early stages, when in the position shown in Figs. 4 and 8 to 10. The further function of the elements, in the position shown in Figs. 9 and 10, is to maintain smoothness and tension until the binder is completely applied to the bunch.

- 10 Where the binder leaf is unusually heavy or stiff the stops 33 are adjusted to permit a greater pressure of engagement of the contacting face of the brush upon the binder. Where the binder leaf is thin and 15 more fragile the stops are adjusted to secure a lighter engagement of the brush upon the binder.

Another important feature in the method and means herein described, is that any 20 foreign substance that may adhere to the surface of the binder is brushed and cleaned away from said surface by the engagement therewith of the several successive bristle points, without in any way injuring the 25 surface of the binder or without pressing the said foreign substance into said surface.

What I claim is:—

1. In the art of cigar bunching, the 30 method which consists in depositing a charge of filler in engagement with the margin of a binder, and then bringing the binder under tension over the filler into engagement with the bunching apron with 35 a regulatable pressure prior to the rolling operation.

2. In the art of cigar bunching, the 40 method which consists in depositing a charge of filler in engagement with the margin of a binder, then bringing the binder under tension over the filler and subjecting the binder to regulatable pressure exerted between a smoothing agent having a plurality of points of independently yielding

pressure and the bunching apron prior to 45 and during the operation of rolling the wrapper about the filler.

3. In a cigar bunching machine, the combination with a bunching table, a roller and apron, of a smoothing element comprising 50 a brush having a plurality of independently yielding bristles or similar elements, forming a binder-engaging surface, means operating said smoothing element to engage the binder prior to and during the 55 rolling operation, and adjustable means for controlling the pressure of said engagement.

4. In a cigar bunching machine, the combination with a bunching table, a roller and apron, of a smoothing element comprising 60 a brush having a plurality of independently yielding bristles or similar elements, forming a binder-engaging surface, means 65 for actuating said smoothing element to cause the same to engage the binder against the apron and roller prior to and during the rolling operation, and adjustable means for regulating the pressure exerted by the smoothing element against the apron and 70 roller.

5. In a cigar bunching machine, the combination of a bunching table, a roller, a 75 roller carriage, an apron, and a binder-smoothing element, comprising a brush, a spring actuated brush supporting frame having pivot and slot connection with the roller carriage.

6. In a cigar bunching machine, the combination of a bunching table, a roller, a 80 roller carriage, an apron, a binder-smoothing element, comprising a brush, a spring actuated brush supporting frame having pivot and slot connection with the roller carriage and an adjustable stop for limiting said spring actuation. 85

BERNARD LIBERMAN.
